HAND SLED

William E. Kidder, Kalamazoo, Mich., assignor to
Kalamazoo Sled Company, Kalamazoo, Mich.

Application November 22, 1937, Serial No. 175,825

6 Claims. (Cl. 230—23)

This invention relates to improvements in hand sleds.

The main objects of this invention are:

First, to provide an improved hand sled particularly of the push type which is light in weight and at the same time very strong and rigid.

Second, to provide a structure having these advantages which is economical in its parts and the assembly thereof.

10 Further objects will appear from the detailed description to follow. The invention is pointed out in the claims. A structure embodying the invention is illustrated in the accompanying drawing, in which:

15 Fig. 1 is a side view of my improved hand sled. Fig. 2 is a plan view thereof.

Fig. 3 is an enlarged fragmentary view partially in section on line 3—3 of Fig. 1 showing details of the runners and the knees.

20 Fig. 3A is an elevation of one of the knees.

Fig. 4 is an enlarged fragmentary view partially in section on line 4—4 of Fig. 2.

Fig. 5 is an enlarged detail section taken on line 5—5 of Fig. 3.

25 Fig. 6 is an enlarged detail section taken on line 6—6 of Fig. 3.

Fig. 7 is an enlarged detail section on line 7—7 of Fig. 3.

The embodiment of my invention illustrated 30 comprises side rails 1, 1 connected by rear cross piece 2 which constitutes a bench for the knees 3, and also by the front cross piece 4 and the intermediate cross piece 5. The rear cross piece 2 is arranged on the under side of the side rails 1, while the cross piece 4 is arranged on the top 35 thereof. The intermediate cross piece 5 is also arranged on the under side of the side rails. Bottom slats 6 are arranged upon and secured to the rear and intermediate cross pieces 2 and 5.

40 The runners 7 are formed of T iron or angle iron of T cross section arranged in an inverted position. The front ends of the runners are upwardly curved at 8 and the front ends of the vertical legs of the runners are cut away to provide horizontally disposed ears 9 which are secured to the under sides of the side rails by bolts or rivets 10. These bolts or rivets also secure the front cross piece 4. The rear ends of the vertical legs of the runners are cut away and the rear ends 45 of the horizontal legs are turned upwardly at 109 to facilitate drawing the sled backward and also to present a rounded surface which is less likely to cause injury than a sharp edge.

45 The knees 3 are formed as sheet metal stampings and are provided with downwardly diverging

legs 11 of channel cross section, as clearly shown in the drawing the web portions of the legs at their lower ends being longitudinally slotted to provide downwardly projecting outer and inner ears 12 and 13 respectively, disposed on opposite sides of the vertical arms 14 of the runner and secured thereto by means of through rivets 15.

50 It will be noted by reference to Figs. 3 and 3A that the lower ends of the legs are curved so that the bottom portions are substantially vertical and their slots are vertical to receive the vertical legs of the runners as clearly shown in Fig. 3 so that the horizontal legs of the runners are presented flatwise to the ground instead of inclined as is quite common practice in sled runners.

55 The outer arms of the channeled legs are provided with outwardly projecting flanges 16 which extend from the top to bottom thereof and are continued under the ears 12. The inner arms of the channeled legs are provided with upwardly widening flanges 17 set at bracing angles to take side strains. These flanges extend at the lower end into the ears 13 and merge into or are connected to the bracket portions 18 of the knees which project inwardly below the bench cross piece 2 and are secured thereto by bolts or rivets 19 passing through the knees, the bench cross pieces, and the side rails, and by the fastening 20, see Fig. 3. This provides a very rigid knee structure which is formed as a sheet metal stamping 30 and may be formed of quite light weight stock. At the same time it is very rigid and capable of 25 withstanding heavy strain. This is of particular advantage in a hand sled as, while strength is required, it is also desirable that the structure 35 be as light as practical.

60 The side bars 21 are disposed in spaced relation above the side rails 1 and are connected thereto by the vertical spindles 22. It will be noted by referring to Fig. 1 that the rear ends of 40 the side bars project substantially beyond the rear ends of the side rails. Cross pieces 23, 24 are arranged between the rear ends of the side rails and side bars respectively, and rigidly secured thereto, fastenings 25 being conventionally 45 shown in Fig. 1. These cross pieces not only serve as tie or brace members for the side rails and the side bars, but they also serve as supports for the back slats 26 which are fixedly secured thereto.

65 The handle comprises a pair of metal side members 27 which have forwardly projecting arms 28 at their lower ends disposed on the inner sides of the side bars 21 and secured thereto as by means of screws 29. The side members 27 have 55

inward offsets 30 at a point above the tops of the back slats 26 which provide a pair of parallel upper portions 31 which are connected at their outer ends by hand bar or grip 32. They are also connected by cross pieces 33 which are arranged in an inclined position at the lower ends of the upper portion 31 of the handle side members and secured thereto by suitable means indicated at 34. This cross piece 33 in the embodiment illustrated is of substantial width and is inclined so that it complements the back slats 26 or constitutes a back member.

It will be noted that the back members 26 are disposed at an angle to the spindles 22 and, being rigidly connected to the side rails and side bars, coact with these elements in forming a triangular brace structure. This is of considerable importance as the various parts are so arranged as to brace and support each other in their normal positions and so that a rigid structure results even when formed of relatively light material, which is of course a feature greatly to be desired in a baby sled and particularly of the push type.

I have illustrated and described my improvements in a practical embodiment thereof. I have not attempted to illustrate or describe certain modifications and adaptations which are possible, as it is believed that this disclosure will enable those skilled in the art to embody or adapt by improvements as may be desired.

Having thus described my invention what I claim as new and desire to secure by Letters Patent is:

1. In a child's sled, the combination of side rails, front and rear, and intermediate cross pieces connecting said side rails, the front cross piece being arranged on top of the side rails and the rear and intermediate cross pieces being arranged on the bottom thereof, runners curved upwardly at their front ends and secured to the under sides of the side rails, a pair of knees formed of sheet metal stampings having downwardly diverging legs secured to said runners and integral inwardly projecting brackets secured to the under side of the rear cross piece, bottom slats secured to said rear and intermediate cross pieces, side bars disposed above said side rails in spaced relation thereto and with their rear ends projecting rearwardly beyond the rear ends of the side rails, vertical spindles connecting said side bars to said side rails, back cross pieces secured between the rear ends of said side rails and side bars, rearwardly inclined back slats secured to said back cross pieces and coacting with said spindles and side bars to provide a triangular bracing structure, and a handle comprising handle side pieces secured to said side bars.

2. In a child's sled, the combination of side rails, front, rear and intermediate cross pieces connecting said side rails, the front cross piece being arranged on top of the side rails and the rear and intermediate cross pieces being arranged on the bottom thereof, runners curved upwardly at their front ends and secured to the under sides of the side rails, a single pair of

knees formed of sheet metal stampings and having downwardly diverging legs secured to said runners and integral inwardly projecting brackets secured to the under side of the rear cross piece only, bottom slats secured to said rear and intermediate cross pieces, side bars disposed above said side rails in spaced relation thereto and with their rear ends projecting rearwardly beyond the rear ends of the side rails, side members connecting said side bars to said side rails, back cross pieces secured between the rear ends of said side rails and side bars, rearwardly inclined back slats secured to said back cross pieces and coacting with said side bars and side members to provide a triangular bracing structure, and a handle comprising handle side pieces secured to said side bars.

3. In a child's sled, the combination of side rails, front and rear and intermediate cross pieces connecting said side rails, the front cross piece being arranged on top of the side rails and the rear and intermediate cross pieces being arranged on the bottom thereof, runners curved upwardly at their front ends and secured to the under sides of the side rails, the securing means for the runners also securing said front cross piece, a pair of knees formed of sheet metal stampings and having downwardly diverging legs secured to said runners and integral inwardly projecting brackets secured to the under side of the rear cross piece, bottom slats secured to said rear and intermediate cross pieces, side bars disposed above said side rails in spaced relation thereto and with their rear ends projecting rearwardly beyond the rear ends of the side rails, vertical spindles connecting said side bars to said side rails, back cross pieces secured between the rear ends of said side rails and side bars, rearwardly inclined back slats secured to said back cross pieces and coacting with said spindles and side bars to provide a triangular bracing structure, and a handle comprising handle side pieces secured to said side bars.

4. In a child's sled, the combination of side rails, cross pieces therefor, runners, a bottom, side bars disposed above said side rails in spaced relation thereto and with their rear ends projecting rearwardly beyond the rear ends of the side rails, side members connecting said side bars to said side rails, back cross pieces secured to the rear ends of said side rails and side bars, a rearwardly inclined back piece secured to said back cross pieces and coacting with said side bars and side members to provide a triangular bracing structure, a handle comprising side pieces having forwardly projecting arms at their lower ends secured to the inner sides of the side bars, said handle side pieces having inwardly offset upper portions, a flat cross piece disposed between said handle side pieces above the back slats and between the inwardly offset upper ends thereof to constitute a tie member therefor and a back member, and a grip disposed between the upper ends of said handle side pieces and secured thereto.

5. In a child's sled, the combination of side rails, cross pieces therefor, runners, a bottom, side bars disposed above said side rails in spaced relation thereto and with their rear ends projecting rearwardly beyond the rear ends of the side rails, side members connecting said side bars to said side rails, back cross pieces secured to the rear ends of said side rails and side bars, and a rearwardly inclined back piece secured to said back cross pieces and coacting with said side bars.

bars and side members to provide a triangular bracing structure.

- 5 6. In a child's sled, the combination of side rails, front and rear and intermediate cross pieces connecting said side rails, runners curved upwardly at their front ends and secured to the front ends of the side rails, a pair of knees secured to the runners and to the rear cross piece

only, bottom slats secured to said rear and intermediate cross pieces, side bars disposed above said side rails in spaced relation thereto, side members connecting said side bars to said side rails, back cross pieces secured to the rear ends of said side rails and side bars, and back slats secured to said back cross pieces.

5 WILLIAM E. KIDDER.
